TREATMENT OF PARAFFIN HYDROCARBONS

Clarence G. Gerhold, Chicago, Ill., assignor to
 Universal Oil Products Company, Chicago, Ill.,
 a corporation of Delaware

Application March 30, 1940, Serial No. 326,870

6 Claims. (Cl. 260—683.4)

This invention relates to the treatment of branch-chain paraffin hydrocarbons with olefins.

In a more specific sense, the invention is concerned with a process for the preparation of motor fuels by alkylating isoparaffins with olefins in the presence of a strong acid, particularly concentrated sulfuric acid or anhydrous hydrogen fluoride.

Cracking processes which are operated principally with the object of producing gasoline from heavier and less valuable petroleum fractions incidentally produce considerable yields of fixed gases, consisting of hydrogen, methane, ethane, propane, and butane, as well as ethylene, propene and butenes in varying quantities and proportions. In many cases these gases are considered to be valuable merely as fuel, although at the present time some of the olefinic constituents are utilized for the manufacture of hydrocarbon derivatives on a commercial basis. There is also a large production of fixed gases in connection with the production and refining of petroleum. Large amounts of paraffinic gases occur as natural gas and well or casinghead gases. These petroleum gases are often utilized only as fuel and from the standpoint of the oil refiner, who is primarily concerned with the manufacture of gasoline and lubricating oils, these gases are mainly considered as waste material, so that considerable experimentation has been conducted to find methods for converting them into liquid products with practical efficiency.

In some cases it may be desirable to decrease the volatility of a certain hydrocarbon motor fuel. This may be accomplished by removing a portion of the light ends by distillation so as to separate such normally liquid hydrocarbons as pentanes and hexanes. The branch-chain members of these two groups of compounds may be reacted with olefins to form isoparaffins of higher molecular weight. These higher molecular weight isoparaffins may be incorporated into the motor fuel, resulting in a decreased volatility as well as an increased volume.

One process in common use at the present time for the conversion of these lighter hydrocarbons into motor fuel consists in the interaction of isoparaffins with olefins in the presence of strong acids such as sulfuric acid or anhydrous hydrogen fluoride. Under appropriate conditions the reaction,

takes place with a minimum production of olefin polymers and heavy products. A method for op-

erating this process well-known to the art uses sulfuric acid as a catalyst and may be briefly described as follows:

Isoparaffins are allowed to react with olefins in the presence of sulfuric acid and a sufficient length of time under the desired conditions of temperature until the olefins have been substantially removed. Isobutane is the isoparaffin commonly used although higher molecular weight isoparaffins will also undergo the reaction referred to. The higher molecular weight isoparaffins are themselves valuable constituents of the motor fuel and are used for alkylation purposes only in the case where their supply is in excess of that needed for volatility requirements. Olefins from C₃ to C₈ inclusive may be used, although the common charging stocks are often limited to C₃ and C₄ olefins. The acid in contact with the hydrocarbons is usually at a concentration somewhere between 88 and 93% titratable acidity. It is kept at this figure by continuously withdrawing part of the used acid and supplying make-up acid of 96 to 100% strength. The charging stock is commingled with an isoparaffin recycle such that the isoparaffin to olefin ratio in the hydrocarbon feed to the acid-hydrocarbon mixture in the reactor is approximately 5 to 1. This ratio in some cases may be as small as 3 to 1, and others as high as 10 to 1. It is somewhat dependent upon the olefins being used.

The process is operated on a continuous basis, complex mixtures of unreacted isoparaffins, motor fuel and heavier products being withdrawn at the same rate as fresh charging stock is being supplied to the reactor. The olefin-isoparaffin alkylation process may be thought of as an absorption of olefin in the acid phase to form an olefin-acid ester which subsequently reacts with the isoparaffin to form a second isoparaffin of higher molecular weight. In order to keep the competing olefin polymerization reaction at a minimum, the ratio of isoparaffins to olefins in the reacting zone is kept high. At the entrance to the reactor, it is common to have present 100 moles of isoparaffin for each mole of olefin being supplied in the charging stock. This ratio may be varied from 80 to 120. The pressure used in the system must be sufficient to keep all constituents in the liquid phase. Pressures higher than this are of no particular aid to the process. The pressure necessary to prevent vaporization in the system depends both on the composition of the feed and on the temperature used. Temperatures between 32 and 50° F. are quite satisfactory and are commonly used. Satisfactory

results have been obtained with temperatures as high as 100° F. The ratio of acid to hydrocarbon is usually 1 to 1 but may vary from 0.7 to 1.0 to 2 to 1. The reactor used in the process consists quite often of a tower equipped with orifice plates, although any method that satisfactorily contacts two immiscible liquids may be used.

It has been shown that anhydrous hydrogen fluoride is also a very effective catalyst in promoting the alkylation of isoparaffins with olefins. Either sulfuric acid or anhydrous hydrogen fluoride may be used in the present invention, although their use is not intended to be on an equivalent basis.

The present invention comprises a modification of the previously described process of alkylating isoparaffins with olefins in the presence of concentrated mineral acid. The essential feature of this invention consists in a separate step in which the used mineral acid is reacted with isoparaffins. It is well-known that the acid layer in alkylations contains dissolved in it complex hydrocarbons and their reaction products with acid, which substances tend to destroy the acid and decrease its period of usefulness. My invention is intended primarily to increase the life of the acid as well as to convert the substances present in it to useful products.

In one specific embodiment, the present invention comprises catalytically interacting isobutane and normal butenes in the presence of concentrated sulfuric acid using a large excess of isobutane to butenes, continuously removing a portion of the acid-hydrocarbon mixture, separating the acid and hydrocarbons, directing the latter to a separating zone for separation into isobutane, normal butane, alkymer of the motor fuel boiling range and heavier products, reacting the used acid with isobutane in a separate reactor and returning the mixture of isobutane and regenerated acid to the alkylating zone.

To indicate in general the type of process flow which characterizes the present invention, the attached drawing has been provided which indicates diagrammatically by the use of conventional interconnected units drawn in side elevation an arrangement of plant apparatus in which operations typical of the process may be carried out.

Referring now to the drawing: The charging stock consisting of a mixture of olefins, isoparaffins, with or without the unreactive normal paraffins as diluents, is supplied to the system through line 1, valve 2 to line 3 wherein it is commingled with the recycle stock of acid and hydrocarbons arising in a manner to be described later. This combined feed and recycle stock is directed through cooler 4 wherein it passes in indirect heat exchange relationship with a cooling medium supplied by line 5, valve 6 and removed by way of line 7, valve 8. The cooled mixture enters reactor 10 by way of line 9. This reactor may contain orifice plates or be of any general construction that will promote thorough mixing of the acid and hydrocarbon layers. The material leaves reactor 10 by way of line 11, a portion being diverted through line 12, valve 17 into settler 18, where a separation of the two phases takes place. The remainder of the mixture leaving reactor 10 is removed from line 11 through line 13 and valve 14, where by means of pump 15, it is commingled with fresh feed entering the system through line 1 as previously described. The used acid separated from the hydrocarbons in settler 18 is removed by way

of line 60, valve 38 and is in part returned to line 16 by way of line 63, valve 64 and in part directed to line 39 wherein it is commingled with isobutane obtained through line 23. This mixture of acid and hydrocarbons is commingled with a recycle stock obtained from reactor 48 through line 49 and valve 50. The resulting mixture of acid and hydrocarbons is directed by means of pump 44 through valve 45 into line 59 10 from which it enters cooler 46 passing in indirect heat exchange relationship with a cooling medium supplied through line 53, valve 54 and removed by way of line 55, valve 56. The cooled mixture enters reactor 48 by means of line 47 15 Reactor 48 may be of the same general construction as reactor 10. In this reactor the iso-butane enters into chemical reaction with the complex hydrocarbon constituents of the acid layer. After sufficient interaction, the mixture of acid and 20 hydrocarbon leaves the reactor by way of line 49, valve 50. A portion is recycled through line 38 while the remainder is directed into line 5 containing control valve 62 from which it passes to line 16. The mixture of hydrocarbons and 25 regenerated acid leaves line 16 entering line 13, wherein it becomes part of the recycle material of reactor 10. Fresh acid may be admitted to the system through line 61 containing control valve 62. 30 The hydrocarbon layer obtained in separator 18 is removed by way of line 19, valve 20 and supplied to fractionating column 21. This column may be of the plate and bubble-cap type or of any general construction known to the art for 35 the rectification by distillation of liquid mixtures. This column removes iso-butane as an overhead product which, after returning a portion to the column for cooling and reflux, is removed through line 23 containing control valve 42 and directed 40 by means of valve 43 to line 39, wherein it is commingled with used acid obtained from separator 18 as previously mentioned. If desired, a portion of this iso-butane may be directed from line 23 to line 57 wherein it passes through valve 58 45 into line 16 being commingled therein with a hydrocarbon-acid mixture obtained from reactor 48. Column 21 is equipped with closed heating coil 22, by means of which heat may be supplied for conducting the necessary vaporization process. 50 The deisobutanized hydrocarbons are removed from column 21, by means of line 24 and after passing through valve 25 enter the second fractionating column 26. The construction of this column may be similar to that of column 21 and is intended primarily to remove any normal butane present from the system. The normal butane is removed from column 26 as an overhead product through line 28, valve 29 and after returning a portion to the column for cooling and reflux, the remainder may be sent to storage. 55 Column 26 is provided with heating coil 27. The higher-boiling hydrocarbons consisting principally of alkymers, leave column 26 through line 30 containing control valve 31 and are directed to column 32 provided with heating coil 37. The purpose of column 32 is to separate the alkymer of motor-fuel boiling range from the heavier boiling hydrocarbons. The alkymer of motor-fuel boiling range is removed from column 32 as an overhead product through line 33 containing control valve 34 and sent to storage. The alkymer boiling above the motor fuel range is removed as a bottoms product from column 32 through line 60 65 35 containing control valve 36. 70 75 The following example is introduced to indi-

cate the character of the results obtainable by the use of the present process, although it is not intended to limit the scope of the process in the exact correspondence with the data submitted.

A residual gas formed by the removal of the isobutylene in a butane-butene fraction by sulfuric acid polymerization may be charged to the process. A typical charging stock of this nature may have the following composition: 18.5% normal butenes, 25.5% iso-butane, 54.8% normal butane and 1.2% pentanes. After commingling sufficient iso-butane obtained from the de-isobutanizer so as to obtain a 5 to 1 isobutane-normal butene ratio, the combined feed and recycle stock may have a composition of 11.1% normal butenes, 55.3% iso-butane and 32.8% normal butane and 0.7% pentanes. This combined feed and hydrocarbons may be mixed with an equal volume of sulfuric acid with a concentration slightly in excess of 93%. The fresh acid fed into the system may have a composition of 98% but after mixing with the used acid, the concentration may be slightly over 93%. The acid and hydrocarbons are continuously removed from the reactor and sent to a cooler to remove the exothermic heat of reaction. The amount of time spent in the reactor is approximately 1.2 minutes per pass and the total residence time may be approximately 25 minutes. Under these conditions 5% of the material leaving the reactor is removed to a separator. Fresh hydrocarbons are supplied at a rate equal to that at which they are being removed from the first reactor system as described above. The acid obtained in the separator will be commingled with an equal volume of iso-butanes and the mixture supplied to the second reactor system. The second reactor is designed in such a manner that the total residence time of the acid and hydrocarbons will be approximately one hour. A recycle-to-removal ratio of 10 to 1 is used. The titratable acidity of the acid is increased from 93.0 to 93.3 by this isobutane treatment. The system operates with an acid consumption of 0.42 pound of acid per gallon of alkylmer produced. The hydrocarbon layer obtained in the separator is de-isobutanized and isobutane commingled with the used acid as shown in the figure. After removal of the isobutane, the normal butane is removed in a second fractionating column and the debutanized product then sent to a fractionating column for separation into motor fuel and heavy bottoms. The amount of heavy bottoms may be approximately

6.5% of the total weight of the alkylate. The alkylate sent to storage contains approximately 86% C₈ and 14% lighter hydrocarbons. It has an initial boiling point of 135° F. and end point of 250. The acid heat will be under 20 and the bromine number less than 0.1. The octane number will be approximately 93 by the C. F. R. motor method.

I claim as my invention:

10. 1. An alkylation process which comprises reacting an isoparaffin with an olefin in the presence of a mineral acid alkylating catalyst in a reaction zone, removing from said zone a mixture of hydrocarbon reaction products and acid catalyst, separating said mixture into a hydrocarbon layer and an acid layer, returning a portion of the acid layer to said reaction zone, subjecting another portion of said acid layer, containing complex hydrocarbon constituents, to reaction with an isoparaffin in the substantial absence of added olefins for a sufficient time to regenerate this portion of the acid catalyst, and supplying the thus regenerated acid to said reaction zone for further use therein as an alkylating catalyst.
15. 2. An alkylation process which comprises reacting an isoparaffin with an olefin in the presence of a mineral acid alkylating catalyst in a reaction zone, removing from said zone a mixture of hydrocarbon reaction products and acid catalyst, separating said mixture into a hydrocarbon layer and an acid layer, returning a portion of the acid layer to said reaction zone, subjecting another portion of said acid layer, containing complex hydrocarbon constituents, to reaction with an isoparaffin in the substantial absence of added olefins for a sufficient time to regenerate this portion of the acid catalyst, and supplying the resultant reaction mixture of hydrocarbons and regenerated acid to said reaction zone.
20. 3. The process as defined in claim 1 further characterized in that said catalyst comprises sulfuric acid.
25. 4. The process as defined in claim 2 further characterized in that said catalyst comprises sulfuric acid.
30. 5. The process as defined in claim 1 further characterized in that said catalyst comprises hydrogen fluoride.
35. 6. The process as defined in claim 2 further characterized in that said catalyst comprises hydrogen fluoride.

CLARENCE G. GERHOLD.
